(57) CLAIM

The ornamental design for a shower head, as shown and described.

DESCRIPTION

FIG. 1 is a perspective view of a shower head, showing our new design;

FIG. 2 is a front elevation view thereof;

FIG. 3 is a rear elevation view thereof;

FIG. 4 is a left side elevation view thereof;

FIG. 5 is a right side view thereof;

FIG. 6 is a top plan view thereof; and,

FIG. 7 is a bottom plan view thereof.

Broken lines formed by equal length dashes shown in the drawings illustrate portions of the shower head that form no part of the claim. Broken lines formed by unequal length dashes (i.e., dash-dot) define bounds of the claimed design and form no part thereof.
